UNITED STATES PATENT OFFICE.

HILDA A. GRENIER, OF ALTADENA, CALIFORNIA.

DESIGN FOR A NOVELTY PINCUSHION DOLL.

Application filed September 29, 1924, Serial No. 10,924. Term of patent 7 years.

To all whom it may concern:

Be it known that I, HILDA A. GRENIER, a citizen of Canada, residing at Altadena, in the county of Los Angeles and State of California, have invented a new, original, and ornamental Design for Novelty Pincushion Doll, of which the following is a specification, reference being had to the accompanying drawing, forming a part thereof.

The figure is a perspective view of a novelty pincushion doll, showing my new design.

I claim:

The ornamental design for a novelty pincushion doll, as shown.

HILDA A. GRENIER.

Witnesses:

JOHN McGINLEY,
LEO GRENIER.
